Ovila G. Hebert
ATTORNEY.

INVENTOR,

UNITED STATES PATENT OFFICE.

OVILA G. HEBERT, OF HOLYOKE, MASSACHUSETTS.

PRINTING APPARATUS.

1,330,374.

Specification of Letters Patent. Patented Feb. 10, 1920.

Application filed January 3, 1916, Serial No. 69,764. Renewed July 21, 1919. Serial No. 312,436.

To all whom it may concern:

Be it known that I, OVILA G. HEBERT, a British subject, and resident of Holyoke, in the county of Hampden and State of Massachusetts, have invented certain new and useful Improvements in Printing Apparatus, of which the following is a full, clear, and exact description.

This invention particularly relates to an improved holder for a line of separate type, whereby the types, more or less in number, to constitute the line may be firmly held, so that pluralities of the holders and type therein may be confined in a carrier, having the nature of a chase, for printing.

The type holder, moreover, comprises means whereby the types are automatically centered therein.

The invention further relates to means whereby the type holders are uniformly centered relatively to the carrier or chase.

The invention is described in conjunction with the accompanying drawings and is set forth in the claim.

25 In the drawings:—

Figure 1 is a perspective view showing the present improved self centering type holder.

Fig. 2 is a horizontal sectional view on line 2—2, Fig. 1.

Fig. 3 is a perspective view of the type holder carrier or chase, especially constructed and adapted with reference to the specially constructed type holders to center the latter in such carrier.

The type holder A comprises an L-shaped bar having a longitudinal slot *a* in its back member *b*, which member rises at right angles from the base member or ledge *d* which forms the bottom support for the type *x*.

B B represent a pair of clamping members slidable in the angular space bordered by the back and base members of the L-shaped bar, in conjunction with which means are provided for imparting approaching and receding movements simultaneously to both of such clamp blocks, so that the line of type, of whatever length the same may be, will be confined centrally of the holder.

The said clamp blocks are provided with tongues *g* *g* extended within the said slot *a*; and they are drilled and tapped with right and left hand threads.

55 D represents a right and left hand screw shaft rotatably mounted on but endwise

non-movable relatively to the back member of the bar, extended lengthwise through said slot *a*, and having the reversely threaded portions thereof engaging, each, the tongue *g* of one of the clamp blocks.

As shown, the plain or unthreaded end portions of the screw shaft D are fitted through alined bores or bearings *h* *h* in the portions *i* *i* of the back member *b* of the holder bar, and are restrained against endwise movements by the collars or shoulders *j* and *k*,—the one *j* being enlarged or in the form of a handle knob and peripherally milled or knurled to constitute a convenient means for the turning of the right and left threaded screw shaft.

The separate types, more or less in number, and to constitute a type line of greater or less length, when placed on the L-shaped holder bar, between the sufficiently separated clamp blocks B B will, when such clamp blocks are brought to approached and confining relations relatively to the types, automatically center the latter on the bar.

Each holder bar A is provided at the middle of its base or ledge member *d* with a depending stud *m*.

This provision is made with reference to means especially provided in the carrier or chase for one or a plurality of the type holders.

The carrier represented in Fig. 3 comprises a plate or body *o*, a fixed end abutment *p*, a clamping bar *q*, and a clamping bar operating screw *t*.

The carrier has in the body plate *o* thereof, centrally and longitudinally, a groove or slot *u*.

The type holders A, to be confined between the clamping members *q* and *p*, and carried by the chase or device comprising such part, have the depending studs *m* thereof engaged in the said groove *u*, whereby all of the type holders will be centered in the carrier, and whereby all of the lines of type of a plurality of the type holders, centered in the latter, will be necessarily centered in the carrier.

The printing devices above described, and shown, are especially useful for use in conjunction with what in the trade is known as a bench embossing machine, in which types set up for brief titles or other matter are used for the printing of "cases" comprised in the backs of books, or for the printing of small sheets or strips of leather

or other material to be stuck on the backs of the book; but as manifest the invention is susceptible of a wider field of utilization.

I claim:—

5 A type holder consisting of an L-shaped bar, a pair of clamp blocks slideable in the angular space bordered by the back and base members of said bar, means for imparting approaching and receding movements simultaneously to both of said clamp blocks, a carrier having means for the confinement

therein of type holders, provided with a groove in its base, and each type holder having a depending stud for a centering engagement in such base groove of the carrier. 15

Signed by me at Springfield, Mass., in presence of two subscribing witnesses.

OVILA G. HEBERT.
